CLAIM

The ornamental design for a seed storage tray, as shown and described.

DESCRIPTION

FIG. 1 is a front, top and side perspective view of the seed storage tray embodying the design of the present invention; FIG. 2 is a front elevational view thereof, the rear elevational view being a mirror image;

FIG. 3 is an end elevational view thereof, the end opposite being a mirror image of the end shown in FIG. 3;

FIG. 4 is a top plan view thereof; and,

FIG. 5 is a bottom plan view thereof.

The broken line showing of packages of seeds in FIG. 2 is for illustrative purposes only and forms no part of the claimed design.
